UNITED STATES PATENT OFFICE

131,682

DESIGN FOR A GARMENT HANGER

John Bolten, Andover, Mass., and Henry Spitz,
Great Neck, N. Y.

Application October 8, 1941, Serial No. 103,680

Term of patent 14 years

To all whom it may concern:

Be it known that we, John Bolten and Henry Spitz, citizens of the United States, residing, respectively at Andover, county of Essex, State of Massachusetts, and at Great Neck, county of Nassau, State of New York, have invented a new, original and ornamental Design for Garment Hangers, of which the following is a specification, reference being had to the accompanying drawing, forming part thereof, wherein:

Fig. 1 is a side elevational view of a garment hanger embodying our new design.

Fig. 2 is a sectional view on the line 2—2, Fig. 1.

We claim:

The ornamental design for a garment hanger, substantially as shown.

JOHN BOLTON.
HENRY SPITZ.
